UNITED STATES PATENT OFFICE.

GEORGE W. BOWMAN, OF MORROW, OHIO.

IMPROVEMENT IN DRIERS.

Specification forming part of Letters Patent No. 147,815, dated February 24, 1874; application filed December 26, 1873.

To all whom it may concern:

Be it known that I, GEORGE W. BOWMAN, of Morrow, Warren county, Ohio, have invented a new and useful Drying Apparatus, of which the following is a specification:

My invention is an improvement in the class of hot closets or ovens formed with suitable racks for holding fruit and other edible substances to be dried, and traversed by flues from a stove or other heating device located beneath or to one side of the chamber; and my improvements comprise devices for insuring an equal and proper distribution of heat.

In the accompanying drawings, Figure 1 is a longitudinal section of a drying-house embodying my improvements. Fig. 2 is a horizontal section of the same at the line XX. Fig. 3 is a transverse section at the line Y Y; and Fig. 4 is a transverse section of the flue at Z Z, Fig. 1.

A represents a drying closet or chamber; B, open slatted floor of same, furnished with a register, B', to regulate the induction of air in the normal operation of the apparatus; C, partition inclosing chimney D; E, intermediate partition; F, cleats for the support of sliding racks or trays G, having customary open slatted bottoms. A characteristic feature of my improvement is the horizontal flue H, which traverses the closet from end to end, and has the represented flattened section, so as to occupy but little vertical room, and yet extend horizontally almost entirely across the closet. A neck, I, on the under side of said flue, near one extremity, admits a pipe, J, from any suitable stove or heater, and another neck, I', rises from the remote end, supports and communicates with a chimney, D, which is flattened, so as to occupy less room longitudinally than transversely of the chamber, as shown. Attached to the under surface of the upper side of the horizontal flue H, directly over the flue J, is a stay and deflecting plate, M, of the be-

lying form shown in Figs. 1 and 4. This plate serves the purpose of deflecting the heat from striking the top of the flue as it enters, and thus warping or stiffening it. This latter action is still further aided by one or more V-formed deflectors, N N' N'', which are fixed to the under surface of the flue-top, and by shiftable dampers or deflectors O O', whose handles o o' extend outside of the flue. P are valves, by which communication may be closed between the flue and chimney, when desired. Q are doors for giving access, and occasionally air, to the interior of the closet. R R' are openings in the top of the closet, which, when the entire heat is desired to be retained, may be closed by flaps or shutters placed over said openings; but when the ventilation, or moderation of heat, is desired, said openings may be partially or wholly uncovered by turning either or both of said flaps or shutters upon their hinges, so as to allow a greater or less area for the escape of heated air. These ventilating flaps or shutters can be hinged to the extreme top board S of the apparatus, and suitable racks or other devices may be applied for retaining said shutters in any desired position.

I claim herein as new and of my invention—

1. In a drying apparatus, the horizontally-flattened horizontal flue H, having the stay and deflecting plate M, arranged as herein set forth, for the purpose specified.

2. The combination of slat bottom B, register B', flat horizontal flue H, induction-pipe I J, discharge-flue D, trays F F, and doors Q Q, as and for the purpose set forth.

3. The combination of the horizontal flat flue H, stay and deflecting plate M, and regulator O o, for the purpose specified.

In testimony of which invention I hereunto set my hand.

Attest: GEORGE W. BOWMAN.

FRANK M. COZAD,

GEO. W. HUTTON.
